UNITED STATES PATENT OFFICE

EUGENE M. BORNHOFT, OF CHICAGO, ILLINOIS

DIRECTORY BOARD

Application filed July 9, 1930. Serial No. 466,757.

The invention relates to bulletin or quotation boards such as are employed by stock and bond brokers or brokers dealing in live stock, wheat, corn and other commodities. Boards of this character are sometimes provided with insertions upon which is applied the name of the stock or bond or the commodity being dealt in and occasionally have the name of the stock or the commodity applied thereto by means of chalk. It has been found extremely difficult to maintain the guide ways for these inserts in a condition which will permit the ready insertion and removal thereof, because particles of chalk become lodged therein and in time clog the guideway and thus interfere with the ready removal and insertion of the inserts.

The invention has as one of its prime objects the provision of a means which prevents particles of chalk which become worn from the crayon during the application or erasure of markings on the board with which the inserts are associated, from lodging in the guideways.

It is an object of the invention to provide each guideway with one or more openings through which the particles of chalk may readily pass and finally, if so desired, be gathered in a trough or other element located at the lowermost end of the board.

It is an object of the invention to provide each of the elements forming part of the guideway with portions which respectively provide a guideway and a support for the insert, the supports being arranged in spaced relation longitudinally of the guideways to thus provide openings through which the particles of chalk may pass as they are worn from the crayon or when erased from the board.

It is an object to provide certain strips which form an element of the guideways with means whereby said strips may be secured to a base board, the means being formed so that each strip is held in spaced relation to the base board to thereby produce a space between the strip and the base board in which the insert may be removably held.

It is a further object of the invention to arrange the insert supports of each guide so

that one support is located in vertical alignment with the supporting means of another super-imposed guide to thus arrange the supporting means in vertical alignment with each other to thus arrange the spaces between said supporting elements in vertical alignment with each other and provide vertically aligned communicating passages through which the particles of chalk may pass and thus prevent their becoming lodged in the guideways.

The invention has these and other objects, all of which will be explained and more readily understood when read in conjunction with the accompanying drawings forming a part hereof which illustrate one embodiment of which the invention is susceptible, it being manifest that changes and modifications may be resorted to without departing from the spirit of the appended claims forming a part hereof.

In the drawings, Fig. 1 is a front elevation of a board embodying the invention applied to the wall of a room, the board having certain portions broken away for the purpose of illustration;

Fig. 2 is a central section taken on line 2—2 of Fig. 1;

Fig. 3 is a section taken on line 3—3 of Fig. 1, showing certain portions of the structure in elevation for the purpose of illustration;

Fig. 4 is a section taken on line 4—4 of Fig. 1;

Fig. 5 is a perspective view of one of the elements employed in producing a guideway;

Fig. 6 is a perspective view of a portion of a base board showing the manner in which the guide element illustrated in Fig. 5 is applied for use, certain portions being broken away for the purpose of illustration; and

Fig. 7 is a section taken on line 7—7 of Fig. 1.

In the embodiment of the invention illustrated in Fig. 1, the board generally designated 10 is applied to a wall 11, the latter of which forms one wall of a room in which the quotation board is located. The quotation board generally designated 10 includes a base board 12, which is preferably formed of some metal of suitable gauge and has the opposed

parallel edges thereof bounded by the frame portions or moulding respectively designated 13 and 14 and has a frame member 15 arranged at one end thereof. The opposite end of the structure such as 16 is open to allow the inserts such as 17 to be introduced between and be removed from pockets designated 18. These pockets 18 are formed by the longitudinally extending members generally designated 19 which are spaced from each other in a vertical direction and thus with the base board provide pockets 18. It is understood that the frame members 13 and 14 are formed so that they operate to complete the pockets 18—18 located at the upper and lower terminations of the board. The structure thus formed which includes the base board 12, the frame comprised of the elements 13, 14 and 15 and the members 19—19 are all secured together to form a unitary device which may be fastened to the wall 11, by means such as screws 20. Each of the members designated 19 which when associated with another similar member and the base board provide guideways for the inserts 17 as most clearly shown in Fig. 5 from which it may be seen that each of these members is comprised of a relatively thin narrow strip 21 which is provided with a plurality of elements generally designated 22 which are disposed in spaced relation to each other longitudinally of the strips and thus provide openings 23 between said elements. These openings provide means through which particles of chalk may pass and thus prevent their lodging in the guideway formed by the strips and the other elements hereinbefore referred to.

By referring particularly to Figs. 5, 6, and 7 it will be noted that each of the elements 22 is formed so that they are substantially T-shaped in cross section which thus provides the portion 24 and the elongated element 25, the latter of which provides a tongue adapted for insertion in an opening 26 such as 26 provided in the base board 12. By referring to Figs. 5, 6 and 7 it will be noted that the tongue portion 25 is of a substantially lesser width than the portion 24 and thus produces a face 27 which rests against the forward face of the base board and holds the strip 21 in spaced relation to the base board to thereby form a groove 28 in which the insert 17 may be removably arranged. The tongue 25 and the aperture or opening 26 provided in the base board are of a dimension which provides a snug fit between the tongue and the material surrounding the opening and therefore when the edge of the tongue is peened over as indicated at 29 the strip designated 19 and its associated elements is substantially held with relation to the base board. It will be noted that when the strip generally designated 19 and its associated elements, generally designated 22, is associated with the

base board that said elements 22 provide a support for the insert 17 which will allow the removal and association of the insert and will cooperate with the base board and the strip 21 to accomplish this last mentioned function.

By referring particularly to Figs. 1, 2 and 4 it will be noted that the elements 13, 14 and 15 which form parts of the frame for the base board 12 are recessed as indicated at 30 (see Fig. 2) to receive the base board, the base board and the element 13 being held in associated relation by means of the screw 31. It will be further noted that the element 13 is provided with a longitudinally extending groove 32 which is formed by the overhanging portion 33 of the element 13 and the base board 12 which will thus provide a guide which is completed by the adjacent member 19. It will be noted that the lower element 14 which forms part of the frame for the device is provided with elements 34 to correspond in construction and function with the portions designated 22 and clearly shown in Figs. 5, 6 and 7 and thus openings 35—35 are provided in the element 14 which align with the openings 23 and allow the particles of chalk to drop from one pocket such as 18 to another and prevent their becoming lodged between the elements forming the pockets 18 and thus interfere with the insertion and removal of the inserts 17.

In the foregoing description of the structure to accomplish the invention, it is manifest that a means is provided whereby the insert 17 may be readily arranged in the pockets and be removed therefrom and in which the pockets are each provided with one or more openings through which the particles of chalk may pass and thus prevent clogging of the guideways. It is further evident that the construction of each of the members such as 19 which form an element of the pocket or guideway is by means of the parts 22 provided with means whereby the strips may be securely fastened to the base board, which in addition, provide means for supporting the inserts and holding the strip 21 in proper relation to the base board.

Having thus described the invention, what I claim and desire to cover by Letters Patent is:

1. In a device of the kind described the combination of a member providing a base board, a plurality of parallel spaced longitudinally extending elements providing guides, and supports for supporting a member adapted to be inserted between said guides, said supports being arranged at one side of said elements at intervals of the length of said elements to provide passages between said supports.

2. In a device of the kind described the combination of a member providing a base

board, a plurality of spaced longitudinally extending guide elements, said elements having means providing for the reception of a member adapted to be inserted between said 5 guide elements, said elements providing supports and said supports including a plurality of members one of which is spaced from the other longitudinally of said guide elements to thereby provide passages between 10 said supports.

3. In a device of the kind described the combination of a member providing a base board, a plurality of longitudinally extending strips secured to said base board, said 15 strips providing guides for inserts adapted to be arranged between said strips, means for connecting said strips to said base board, said means including elements arranged lengthwise of said strips in spaced relation 20 to each other to thereby provide a passage between pairs of said connecting means.

4. In a device of the kind described the combination of a member providing a base board, a plurality of longitudinally extending strips secured to said base board, said 25 strips providing guides for inserts adapted to be arranged between said strips, means for connecting said strips to said base board, said means including elements arranged length- 30 wise of said strips in spaced relation to each other to thereby provide a passage between pairs of said connecting means, said connecting means providing means for engaging and supporting said inserts.

35 5. In a device of the kind described the combination of a strip adapted to be secured to a base board, said strip having a plurality of elements extending from one face thereof which are of a lesser width than said strip, 40 one of said elements being arranged in spaced relation to another lengthwise of said strip and having means for securing said strip in spaced relation to said base board and providing supporting means for an insert arranged 45 in said space, said strip providing an element of a guide for said insert.

60 6. In a device of the kind described, the combination of a strip adapted to be secured to a base board, the board being apertured for the reception of an element of said strip, said strip having a plurality of elements extending from one face thereof, one of said elements being arranged in spaced relation to another lengthwise of said strip, 55 said elements having a portion which is secured to said strip and is of a lesser width than said strip and having a portion extending therefrom providing means adapted to be inserted in an aperture provided in said base to secure said strip to said base.

65 7. In a device of the kind described the combination of a member providing a base board, a plurality of longitudinally extending spaced strips secured to said base board, said strips having a plurality of elements

which are of lesser width than said strips extending therefrom toward said base board providing means for securing said strips in spaced relation to said base board, said elements of one strip being arranged in spaced 70 relation to each other longitudinally of said strip, and providing spaces between said elements and said spaces of one strip being arranged in substantial vertical alignment with said spaces of an adjacent strip and providing 75 vertical aligned passages.

8. In a device of the kind described, the combination of a base board having apertures provided therein, a strip, members extending from one face of said strip, said members being of a lesser width than said strip and cooperating with said strip and board to provide a guide, an element extending from each of said members adapted to be arranged in said apertures in said board, said element 80 providing means for securing said strip to said board, and said members being arranged in spaced relation to each other lengthwise of said strip to provide an opening between 85 said members.

In witness whereof I hereunto subscribe my name this 3rd day of July, A. D. 1930.

EUGENE M. BORNHOFT.
